UNITED STATES PATENT OFFICE.

JAMES C. ANDERSON, OF HIGHLAND PARK, ILLINOIS.

STAMP-MILL MACHINERY.

No. 852,756.

Specification of Letters Patent.

Patented May 7, 1907.

Application filed May 23, 1904. Serial No. 209,264.

To all whom it may concern:

Be it known that I, JAMES C. ANDERSON, a citizen of the United States, residing at Highland Park, in the county of Lake and State of Illinois, have invented certain new and useful Improvements in Stamp-Mill Machinery; and I do hereby declare the following to be a full, clear, and exact description of the invention, such as will enable others skilled in the art to which it appertains to make and use the same.

My invention relates to certain new and useful improvements in "stamp mill machinery" of that class shown and described in Letters Patent No. 743,800, granted to me November 10, 1903, and which was designed to carry out a "method of crushing and stamping ores" fully illustrated and described in Letters Patent No. 743,799, also granted to me November 10, 1903. This last mentioned Letters Patent involves the generic principle of lifting the stamp by the direct application of a suitable column or head of water delivered to the point of application of power, through a pipe or similar closed conduit, and then permitting the water to escape and the stamp to descend by gravity and then utilizing the escaping water for "pulping" the crushed ore in the mortar. The first mentioned Letters Patent illustrates and describes a stamp mill consisting of one or more mortars and stamps mounted in a suitable frame; mechanical means for lifting the stamps; and, a closed conduit for directing a column of water from an elevated source by gravity alone, directly to the stamp lifting mechanism, and it also shows and describes mechanism through the medium of which the impact force of the falling dies is utilized to operate a primary ore crusher.

My present invention has for its object to embody all of the generic principles of construction and operation set forth in the two Letters Patents referred to and to utilize the momentum shock produced by the fall of each stamp to lift the other mortar and its anvil against the stamp above the same, and to produce a vibratory or rocking motion of the two mortars resulting in a series of alternating blows of decreasing power between the stamps and anvils, before the second stamp is lifted and allowed to fall by gravity to produce like results, whereby the ore within the respective mortars is more thoroughly comminuted than would be the result of sin-

gle alternating blows by the stamps and the comminuted ore is tossed and mixed within the mortars.

My invention also has for its object to render the construction simple and economic and the apparatus capable of ready transportation.

With these ends in view my invention consists broadly in combining with a pair of stamps adapted to be lifted by suitable mechanism and permitted to fall by gravity, a mortar located beneath each of said stamps, and mounted upon the opposite ends of a vibratory support or rocker, so that the momentum shock of each stamp within its respective mortar will while crushing the ore in said mortar, also cause the opposite mortar with its anvil to rise and deliver an upward blow against the stamp above said mortar and a vibratory motion of the two mortars whereby a series of alternating blows of gradually decreasing power are produced and the ore finely comminuted and mixed, all as will be hereinafter more fully described.

My invention also consists in the details of construction and arrangements employed for carrying out the generic principles described.

In order that those skilled in the art to which my invention appertains may know how to make and use my improved stamp mill machinery and fully appreciate its advantages, I will proceed to describe the same referring by numerals to the accompanying drawings, in which,

Figure 1, is a side elevation of a stamp mill and crusher involving my invention, looking from the left of Fig. 2. Fig. 2, is a front elevation partly in section, said section being taken on the line $x-x$ of Fig. 4. Fig. 3, is a rear elevation partly in section, said section being taken on the line $y-y$ of Fig. 1. Fig. 4, is a top plan view. Fig. 5, is a detail horizontal section taken on the line $z-z$, of Fig. 3. Fig. 6, is a detail section on enlarged scale, taken on the line $a-a$ of Fig. 7, and Fig. 7, is a similar view taken on the line $b-b$, of Fig. 6.

Similar reference numerals indicate like parts in the several figures of the drawings.

1, is the base or bed plate, preferably composed of cast iron formed with an elevated rocker support 2 and formed with a surrounding strengthening flange 3. The rocker support 2, springs from parallel vertical ribs 4, provided with recesses adapted

to receive anvil blocks 5, mounted upon suitable cushions 6, located in said recesses.

7, is a rocker mounted upon the rocker support 2, the said rocker and its support being of the form shown most clearly at Fig. 3, in order that the rocker may freely vibrate upon its support. The ribs 4 and the extremities of the rocker 7, are in the same vertical plane with vertical center of the mortars 8, which are mounted within the frame consisting of the bed plate 1, four posts 9, two parallel arch castings 10, two parallel cross beams 11, and two transverse tie rods 12. The lower ends of the posts 9 are formed with shoulders adapted to rest upon the bed plate and pass through vertical bosses 13, of the bed plate and are threaded to receive nuts 14 by which they are rigidly secured in place. The upper ends of these posts are similarly shouldered to contact lugs 15, on the cross beams 11, and are secured rigidly thereto by nuts 16.

The arch castings are formed with a horizontal flange 17 at each end and are secured to the cross beams 11, by suitable bolts 18, and the transverse tie rods 12 are shouldered at each end and pass through the cross beams 11, being secured in place by nuts 19. One of the arch-shaped castings is extended upwardly as shown at 20 and trends inwardly at the upper portion to constitute a bearing 21 (see Figs. 1 and 4) for a walking beam lever 22, formed with a hub 23, and spanner-shaped or bifurcated crank arm 24.

35 The walking beam lever 22 is vibratively secured to this arch shaped casting by a bolt 25 threaded through the bearing 21 and secured in place by a nut 26 (see Fig. 4). Each end of the walking beam lever 22 is formed with a lateral extension or hub 27, to which is attached an oscillating latch 28, which is formed with a hub 29, and an axial cylindrical shank 30 adapted to pass through the extension or hub 27 of the walking beam 45 and is secured in position by a cotter pin 31, or in any other suitable manner adapting said latch to an oscillating or vibrative movement. This latch is of a bell-crank order, its vertical arm having a flat horizontal upper 50 face adapted to contact with the shoulder at the under extremity of the collar 32 of the stem 33 of the stamp 34, and its horizontal arm bifurcated to straddle the web of an I-shaped upper portion 35, of a spring latch 55 operating rod 36 mounted in lugs 37 on the outer side of a casting 38. This casting 38, is secured by bolts 39 to a casting 40 which is in turn secured to flanges 41 of the arch-shaped castings 10, and constitutes part of 60 the bearing or housing of the stems 33 of the stamps 34. The casting 38 is formed in two parts and the outer portion which is provided with the lugs 37, is secured to that portion which is held in position by the bolts 39, by 65 transverse bolts 42, as shown at Fig. 1.

43, is a coil spring surrounding the spring latch operating rod 36 and is confined between the lower lug 34 of the casting 38 and check nuts 43^x on the rod 36, as shown at Fig. 1.

70 The mortars 8 are provided with dies 44, and at their upper ends are closed by caps 45, secured in position by vertical screw bolts 46 threaded into lugs 47 (see Fig. 6), on the mortars. These caps 45, are formed with vertical extensions 48 which constitute one-half of the housing of the inner ends of each pair of the toggles 49 by which the crusher is operated, as will be presently described, and caps 50 secured by screw bolts 51, to the 75 extension 48 of the cap, constitutes the other half of the housings of the inner ends of the toggles.

80 The outer ends of each pair of the toggles are secured by caps 52 respectively, to the lower ends of the vibrative jaws 53 of the crusher and to the cross beams 11, (as best shown in Figs. 3 and 6).

85 Each stamp is provided with a shoe 54, in the usual manner and the crusher jaws are 90 vibratively secured at their upper ends by caps 56 to cylindrical supports 57, mounted in the arch castings 10. Parallel vertical extensions 53 of the castings 10, constitute the sides of the crusher hopper and to the 95 lower extremities of said extensions is secured by bolts 59, a feeder 60 formed with a central hollow deflecting rib 61, (see Fig. 3), so that as the ore leaves the crusher, it will be delivered to the dies of both mortars 100 through the throats 62 in an obvious manner.

105 From this construction, it will be readily understood that when one of the stamps falls and contacts with the die 44 at the bottom of the mortar, said mortar is forced downwardly and consequently the toggles are first straightened, which causes the lower end of the jaw of the crusher on that side to be vibrated inwardly and as the mortar 110 causes the rocker 7 to vibrate upon its support 2, the opposite mortar is lifted and the similar toggles connected with the cap of that mortar are simultaneously, and to the same extent straightened and hence the 115 crusher jaw on that side also vibrates inwardly. The continuation of the downward movement of the first named mortar and the corresponding continued upward movement of the other mortar causes the toggles connected with the respective mortars to buckle and to carry the lower ends of the two jaws away from each other, and these vibrative movements of the two jaws alternately crushes the ore and then releases or feeds it 120 to the feeder 60 and through the throats 62, to the two mortars.

125 The timing of the vibration of the walking beam lever 22, is predeterminedly such as to permit of this described pulsatory action of 130

the mortars and stamps, before each of the stamps is positively lifted by the walking beam lever.

Thus as will be readily understood, and as described in the Letters Patent hereinbefore referred to, the weight and momentum shock of each stamp is utilized to operate the crusher, and with the mortars mounted upon the vibrative rocker according to my present invention, the momentum shock also operates to multiply the blows between the stamps and the dies and to likewise cause each of the stamps to be partly lifted before the stamp lifting devices come into action.

Particular attention is directed to the advantageous results flowing from the fact that the two mortars are mounted upon opposite ends of the rocker 7.

It will be readily seen that when one of the stamps descends upon the anvil of the mortar below said stamp, a crushing blow is given to the ore resting upon such anvil and the mortar is forced downward by the blow of the

stamp, and consequently that end of the rocker upon which said mortar is mounted will be forced downward and that the opposite end will be correspondingly lifted against the stamp in alignment therewith, and which

is at a state of rest, and consequently the blow of the first mentioned stamp is thus transmitted to the ore resting upon the anvil in the second mortar, and at the same time said transmitted blow operates to lift the last

mentioned stamp into position to be acted upon by the stamp lifting mechanism which is accordingly timed to thus act. When this stamp has been lifted and is released and falls by gravity the action just explained is obvi-

ously reversed. This vibratory action of the mortars and the alternating blows given by the stamps also serves to agitate the broken ore in the mortars which is a desirable condition.

The stems 33 of the stamps 34, reciprocate vertically in the bearings between the two parts of the castings 38, and pass through a suitable opening 63 (see Fig. 7), of the caps 45.

The mortars 8, have their inner sides or walls extended to constitute a throat 62, so that as the ore leaves the crusher it will be delivered to dies of both mortars through said throats as previously explained. The mortars 8 are formed with gateways or openings on the three outer sides in which are located suitable screens 63^x, substantially as and for the purpose shown and described in Letters Patent No. 743,800, hereinbefore referred to.

The means for applying the column of water directly to the die lifting mechanism consists of the closed conduit or pipe 64, a hydraulic cylinder 65, and a piston 66. The

water conducted through the closed conduit

or pipe 64, is fed alternately to opposite sides of the piston 66 through ports 67 and 68, by an oscillating valve 70, which is operated by a controller valve 71, as fully illustrated and described in Letters Patent No. 743,800, hereinbefore referred to.

The outer end of the hydraulic piston stem 72 is secured to a cross-head 73, (see Fig. 4), to the ends of which are journaled rods 74, the opposite ends of which are pivotally connected with wrist pins or lugs 75 on the bifurcated crank arm 24, of the walking beam lever 22. One of the rods 74, is extended as shown at 76, and constructed in a similar manner to the vertical rod shown in Letters Patent No. 743,800, and designated therein as E', to operate the crank arm 77, of the controller valve 71, and the water fed from an altitude through the pipe or conduit 64, is delivered to the hydraulic piston valve, 85 and the controller valve and exhausted and carried to the mortars for pulping purposes by suitable branch pipes all as fully set forth in the Letters Patent No. 743,800, referred to.

As the piston 66 is reciprocated the walking beam lever 22 is vibrated through the medium of the piston stem 72, cross head 73, and bifurcated crank arm 24, in an obvious manner, and as said walking beam lever is vibrated it causes the stamps 34 to be alternately lifted and released so that they may fall by gravity to stamp the ore delivered from the crusher onto the dies 44, in the mortars 8.

While I have in a general way described the action of the die lifting mechanism operated through the medium of a column of water controlled by suitable valves, and have referred specifically to my prior Letters Patent No. 743,800, as illustrating and describing the action of the controlling valves and their interdependence and co-operation, I do not wish to be limited in my present invention to any of such details of construction or to the employment of any particular motive force for lifting the dies, as the genus of my present invention resides more particularly in the features of construction by means of which I am enabled to utilize the momentum shock of the falling stamps, not only for the purpose of operating an ore crusher arranged above the mortars, but to likewise, and primarily, utilize such momentum shock or force to multiply the blows exerted upon the ore in the mortars, and to secondarily, lift each stamp through a part of its upward travel. I deem it important in this connection, however, to call especial attention to the particular mechanism by means of which the stamps are lifted and released, and which I have found to be highly satisfactory and efficient and to which I have in a general way heretofore referred to.

The oscillating latches 28 which are vibratively connected to the ends of the walking

beam lever 22, are so pivoted thereto that the upper portion or head of the latch will normally lie within the path of the vertical movement of the collars 32, on the stamp stem 33, so that the flat horizontal part of the latch heads, will contact with the lower edge of the collars, as shown best on the right hand side of Fig. 3, and in position to lift the stamp. With this relation between the latch 28, and the collar 32, when the end of the walking beam lever 22, rises, the stamp stem 33, will necessarily be lifted, and just before the end of the walking beam lever reaches the limit of its upward movement, and by reason of the pivotal relation between it and the latch 28, the latter will be vibrated out of frictional contact with the collar 32, thus permitting the stamp to descend by gravity. Should the latch, for any improbable reason, fail to be vibrated out of contact with the collar 32, before the end of the walking beam lever reaches the limit of its upward movement,—as, for instance, shown on the left hand side of Fig. 3,—auxiliary means are provided to secure the proper outward or releasing movement of the latch 28. In this position the horizontal bifurcated arm of the latch straddles the I-shaped upper portion 35 of the spring operating rod 36, which is so adjusted by the check nuts 43, that just as the end of the walking beam lever reaches the limit of its upward movement, (as shown at the left of Fig. 3), the bifurcated arm of the latch will contact with the under surface of the I-head of the rod 36, which will cause the latch to vibrate upon its pivot to release the collar 32, and permit the stamp to fall. The opposite end of the walking beam lever 22, having reached its lowest movement, the bifurcated arm of the latch on that side, has contacted with the upper surface of the lower projection of the I-piece 35, and if the latch should not have resumed its normal position as heretofore explained, such contact will insure its assuming such position and with its head below the projecting shoulder of the collar 32, in position to lift the stamp.

Having described the construction and operation of my improved stamp mill machinery, what I claim as new and desire to secure by Letters Patent, is:

1. In a stamp mill, a pair of vertically movable stamps, a pair of vertically movable mortars, each located below and in alignment with the respective stamps; and a power transmitting rocker or lever mounted vibratively upon the base of the machine and supporting at each end thereof one of the vertically movable mortars, whereby the momentum shock produced by the descent of each stamp alternately, will through the medium of the vibrative rocker cause the material in the opposite mortar to be crushed between said mortar and the stamp

in alinement therewith, substantially as hereinbefore set forth.

2. In a stamp mill such as described, in combination with a pair of vertically reciprocating stamps and a pair of vertically movable mortars mounted upon the opposite ends of a vibrating rocker or lever, a pair of crusher jaws vibratively mounted in the frame above the mortars and connected at their lower ends by toggle levers to the mortars and frame respectively, substantially as and for the purposes set forth.

3. In a stamp mill such as described, in combination with a pair of stamps adapted to vertical reciprocating movement and provided with collars or shoulders near the upper ends of the stems thereof, a walking beam lever vibratively mounted upon the frame intermediate the stamps and provided at each end with a pivotally connected oscillating latch adapted to contact with and to release the collars or shoulders upon the upper ends of the stamp stems, substantially as hereinbefore set forth.

4. In combination with the vertically reciprocating stamps, vibrating walking beam lever, and oscillating latches pivotally connected to each end of the walking beam lever, means adjustably connected with the frame for positively oscillating the latches, substantially as hereinbefore set forth.

5. In combination with a pair of vertically reciprocating stamps; corresponding mortars and dies mounted upon the opposite ends of a vibrating lever or rocker; and means for alternately lifting said stamps; means for connecting the lifting mechanism with the stamps and releasing the same, said means adapted to alternately release each of said stamps prior to making lifting engagement with the other, substantially as and for the purpose set forth.

6. In a stamp mill, a pair of stamps adapted to be positively lifted and to descend by gravity upon a mass of ore in a mortar beneath the same; and a pair of mortars pivotally mounted one upon each end of a vibrative power transmitting rocker or lever, whereby the momentum shock delivered by each stamp within its respective mortar will cause the rocker or lever to vibrate and deliver a crushing blow to the ore in the opposite mortar and against the stamp in alinement therewith, substantially as hereinbefore set forth.

7. In a stamp mill such as described, in combination with a pair of vertically reciprocating stamps and a pair of mortars mounted upon opposite ends of a rocker or vibrating lever, a crusher located adjacent to the movable mortars and means intermediate the mortars and the crusher for vibratively operating the jaws of the crusher whereby the vibrative movements of the supporting rocker are utilized to apply motive force to

the crusher, substantially as hereinbefore set forth.

8. In a stamp mill such as described, a pair of vertically reciprocating stamps; a pair of vertically movable mortars in alignment with the respective stamps; a rocker or lever mounted vibratively intermediate of the mortars and pivotally supporting one of the mortars at each end thereof; and a combined anvil or stop below each end of the rocker or lever for limiting the extent of the vibrative movement of the same, substantially as hereinbefore set forth.

9. In a stamp mill, a pair of reciprocating stamps, a pair of movable or reciprocating mortars; and a vibrative power transmitting rocker or lever pivotally connected at each extremity with one of the mortars, whereby the movement imparted alternately to each of the mortars by the blow of its respective stamp will cause said blow to be transmitted to the other mortar to produce a crushing effect upon the contents and against its respective stamp, substantially as and for the purpose set forth.

10. In a stamp mill such as described, a pair of vertically reciprocating stamps; a pair of vertically movable mortars; a walking beam lever vibratively journaled in the frame; means intermediate each end of the walking beam lever and the vertically reciprocating stamps for lifting and releasing the stamps; a rigid radial arm extending from the walking beam lever to and connected with a reciprocating piston; a reciprocating piston

within a horizontally disposed hydraulic cylinder; a horizontally disposed oscillating valve connected by suitable supply and exhaust ports with the hydraulic cylinder and with water supply and exhaust conduits; a vertically disposed cylinder connected with water supply and exhaust conduits and provided with a reciprocating piston; means intermediate the vertically reciprocating piston valve and the horizontally disposed valve, for controlling the movements of the latter; and closed water conduits or pipes connecting with each of the valves, substantially as and for the purpose set forth.

11. In a stamp mill such as described, in combination with a pair of stamps adapted to vertical reciprocating movement and provided with collars or shoulders near the upper ends of the stems thereof; a walking beam lever vibratively mounted upon the frame intermediate of the stamps; oscillating latches pivotally connected with the ends of the walking beam lever and adapted to contact with and release the collars or shoulders on the stamp stems, and means for positively causing the latches to release the collars or shoulders upon the stems of the stamps, substantially as hereinbefore set forth.

In testimony whereof, I have signed my name to this specification in the presence of two subscribing witnesses.

JAMES C. ANDERSON.
